CHARLES C. HANSEN, OF EASTON, PENNSYLVANIA, ASSIGNOR TO INGERSOLL-RAND COMPANY, OF NEW YORK, N. Y., A CORPORATION OF NEW JERSEY.

AUTOMATIC FEED FOR PERCUSSIVE DRILLS.

1,074,320.

Specification of Letters Patent. Patented Sept. 30, 1913.

Application filed July 19, 1912. Serial No. 710,373.

To all whom it may concern:

Be it known that I, CHARLES C. HANSEN, a citizen of the United States, residing in Easton, in the county of Northampton and 5 State of Pennsylvania, have invented certain new and useful Improvements in Automatic Feeds for Percussive Drills, of which the following is a specification.

This invention relates to percussive drills 10 and more particularly to a rack and pawl construction for automatically feeding such drills toward their work. Feeding mechanism of this type is not new and it is old in the art to provide a stationary rack secured 15 to a support on which a hammer drill is slidably mounted and to provide the drill with pawls which engage the stationary rack.

The object of the present invention is to 20 provide a rack and pawl feeding means of new and improved construction which allows the rack and pawl or pawls to be quickly and simply disengaged from each other when it is desired to return the drill 25 to the beginning of its feed and also to provide a means whereby the drill can be held in its rearmost position when it is desired to move the drill, change steels, or do anything else requiring the drill to be fixedly held.

30 With this object in view I have devised a feeding means the practical embodiment of which is shown in the accompanying drawings in which—

Figure 1 shows the plan of the complete 35 drill Fig. 2 shows the section through Fig. 1 on the line II—II, showing the feeding rack in elevation Fig. 3 shows an enlarged section of the rear part of the drill showing the pawl mechanism and the rack 40 turned to hold the drill in its rearmost position and Fig. 4 is a section through the line IV—IV of Fig. 3 showing the rear end of the drill in elevation.

The tool as shown consists of a hammer 45 drill 1 of ordinary construction, slidably mounted by means of flanges 2 secured thereto to which slide in grooves in the supporting shell 3. The lower part of the backhead 4 of the drill is extended rearwardly and its 50 lower face is provided with three transversely bored sockets in which are mounted three pawls 6, 7 and 8, two of which, 6 and 7, extend rearwardly from their sockets and the other 8 extends forwardly therefrom. 55 These pawls are secured in position by plates

9 and 10 which are fastened to the backhead by bolts 11 and contact with the side faces of the pawls, which extend completely across the width of the backhead. Spring pressed plungers 12 mounted in the backhead press 60 the pawls into operative position. Coöperating with these pawls and rotatably mounted in bearings 13, 14 and 15 on the drill shell is a rack 16, which consists of a round bar a portion of the circumference of which is 65 provided with a row of teeth 17 extending the greater part of the length of the bar and having forwardly facing surfaces for engaging the pawls 6 and 7. The pawls 6 and 7 are so spaced that they do not both engage 70 the teeth 17 at the same time. On the opposite side of the bar near the rear end thereof are a few teeth 18 having backwardly facing surfaces for engaging the pawl 8. The rest of the surface of the bar is entirely smooth. 75

The bearing 15 is provided with a stop mechanism consisting of a spring pressed ball 19 which is adapted to engage opposite recesses 20 in the surfaces of the rack bar to hold it in any desired position. The handle 80 21 is secured to the rear end of the rack bar providing a means to rotate it.

In operation when it is desired to start the drill in its work the rack bar 16 is turned to the position shown in Fig. 2 with the 85 teeth 17 uppermost and in position to be engaged by the pawls 6 and 7. The drill 1 will feed forwardly when the air is turned on by the impact of the piston on the front head and the pawls 6 and 7 will engage teeth 90 17 and prevent any backward movement of the drill. When the drill has reached the limit of its forward movement which will be when the pawl 6 engages the last of the teeth 17, the rack 16 can be rotated by means 95 of the handle 21 so that the pawls 6 and 7 engage the smooth surface of the rack bar thus enabling the drill to be slid backwardly to its rearmost position without any hindrance from the pawls, this rotation being possible when the drill is at any position on the shell. If it is desired to hold the drill in its rearmost position the rack bar 16 can be turned so that the teeth 18 are uppermost 100 as in Fig. 3 when the pawl 8 will come into operation engaging one of the teeth 18 and holding the drill securely in position on the supporting shell.

Although the rack bar is here shown secured to and rotatable on the supporting 110

means and the pawls attached to the drill the positions of the rack and pawl could be reversed without invention and the rack bar secured to the drill while the pawls could be 5 fastened on the supporting means, and it is to be understood that the present showing discloses but one modification of my invention and other modifications such as that mentioned above are included in the spirit 10 and scope of the invention as expressed in the claims.

What I claim is:

1. In combination with a hammer drill 15 slidably mounted on a supporting means, a rack and pawl mechanism for automatically feeding said drill forward, said rack comprising a rotatably mounted bar having a portion of its surface provided with an extended row of feeding teeth, a smooth portion, and a portion near its rear end pro-

vided with one or more holding teeth, said pawl mechanism comprising backwardly extending pawls for engaging said feeding teeth and a forwardly extending pawl for engaging said holding teeth. 25

2. In combination a support, a drill slidably mounted thereon, a rack bar rotatably mounted on said support, said rack bar having one portion of its surface provided with feeding teeth, a separate portion with holding teeth disposed oppositely to said feeding teeth, two sets of pawls secured to said drill for engaging said teeth, and means to rotate said rack bar from a position of engagement with one set of pawls, to engagement with 30 the other set. 35

CHARLES C. HANSEN.
